DESIGN FOR A HANDLE STICK FOR A CONFECTIONERY PRODUCT

Joseph V. Cariffe, Chicago, Ill., assignor to the
Joe Lowe Corporation, New York, N. Y., a cor-
poration of Delaware

Application February 3, 1936, Serial No. 60,961

Term of patent 14 years

To all whom it may concern:

Be it known that I, Joseph V. Cariffe, a citizen
of the United States and resident of Chicago,
Illinois, have invented a certain new, original,
and ornamental Design for a Handle Stick for a
Confectionery Product, of which the following is
a specification, reference being had to the ac-
companying drawing, forming part thereof.

The figure is a perspective view of a handle
stick for a confectionery product showing my
new design.

The design is characterized by its arcuate curves
of the same radii, providing a circular end and
continuous reverse arcuate indentures symmetrically
arranged on opposite sides of the handle
stick adjacent the ends thereof.

What I claim is:

The ornamental design for a handle stick for a
confectionery product substantially as shown and
described.

JOSEPH V. CARIFFE.
